UNITED STATES PATENT OFFICE.

HULDREICH KELLER, OF ZURICH, SWITZERLAND, ASSIGNOR TO GENERAL ELECTRIC COMPANY, A CORPORATION OF NEW YORK.

SURFACE CONDENSING APPARATUS.

1,063,695.

Specification of Letters Patent.

Patented June 3, 1913.

Application filed July 15, 1909. Serial No. 507,684.

To all whom it may concern:

Be it known that I, HULDREICH KELLER, a citizen of Switzerland, residing at Zurich, Switzerland, have invented certain new and useful Improvements in Surface Condensing Apparatus, of which the following is a specification.

The present invention relates to surface condensing systems for condensing the exhaust steam from a turbine or other prime mover. Such a system requires a pump to remove the air contained in the steam to be condensed if the best effects are to be obtained. The type of pump known as a 15 "centrifugal throwing pump" has many advantages for such installations but there are certain conditions under which it operates at a disadvantage. I mean by a "centrifugal throwing pump" one in which water or 20 some other medium heavier than air is discharged by an impeller and in so doing acts to compress air or other gas. If the pump is so situated that the throwing water can freely flow from the pump after performing 25 its work no difficulty is experienced. On the other hand if the pump is located in a deep condenser pit from which the throwing water cannot freely flow, a special rotary pump has been used to remove said water. 30 The use of such a pump is objectionable on account of initial cost and that of maintenance and operation. To obviate the use of the said special rotary pump, the air pump has been arranged to receive its supply of 35 throwing water from a receptacle located at a somewhat lower point than the pump and into which the pump discharges, the water being used over and over again. This arrangement is defective for the reason that 40 the water soon becomes heated due to the action of the throwing pump unless the receptacle is unduly large. In some cases such receptacles cannot be used at all owing to the lack of room. In any event in a moder- 45 ate size installation the mere radiation and conduction of heat is insufficient to keep the temperature as low as it should be. Owing to the heating of said water by the pump the vacuum is impaired to the detriment of the 50 economy of the machine discharging into the condenser.

I have invented or discovered an arrangement whereby throwing air pumps can be effectively employed either with or without 55 small vessels into which said pumps can dis-

charge their throwing water, and this without the use of special rotary pumps serving only as a means for handling the throwing water after it has performed its work on the one hand or unduly increasing the temperature of the throwing water or using large vessels on the other. I may, for example, use one form of the invention in those installations where space is at a premium, and the other form having the vessel where space 60 is less valuable. The use of a vessel as I arrange it has certain advantages that will appear more fully hereinafter. The fundamental idea involved in my invention is to provide an abundant supply of cool water 65 for the throwing pump, at the same time overcoming the objections above noted.

For a consideration of what I believe to be novel and my invention, attention is directed to the accompanying description and 70 claims appended thereto.

In the accompanying drawings which are illustrative of my invention, Figure 1 illustrates a condensing system wherein the circulating water conduit system and the 80 throwing pump are connected in parallel as regards the water supply, and Fig. 2 is an arrangement similar to that shown in Fig. 1, except that an equalizing vessel is interposed between the throwing pump and the source 85 of water supply.

1 indicates a surface condenser of any usual or suitable type to which the steam to be condensed is admitted by the conduit 2. The interior of the condenser is provided 90 with tubes or passages 3 over which the steam to be condensed passes and through which the cooling or condensing water circulates. The circulation of cooling water through the condenser is maintained by the 95 circulating pump 4, inlet 5 and outlet 6. The cooling water is supplied to the pump by the pipe 7 which may be connected to a cooling tower, reservoir or other source of water supply.

8 indicates the centrifugal throwing pump for removing air from the condenser. The pump receives its throwing water from the pipe 9 that is connected to the pipe 7 leading from the supply of circulating water. 105 In the pipe 9 is a valve or other device 10 for restricting or regulating the passage of water to the suction side of the pump 8. The air to be removed from the condenser flows by the pipe 11 to the throwing pump 110.

8 wherein it is acted upon by the water discharged by the pump. From the pump the mixture passes by the conduit 12 into a jet device or constriction 13 in the pipe leading to the suction side of the circulating pump. The use of this jet device or restriction arranged as shown enables the circulating pump to draw off the throwing water without the use of a special rotary pump. In the pipe 12 is placed a check valve 14 to prevent water from the centrifugal circulating pump or its source of supply from flowing backward to the throwing pump. The circulating pump and the throwing pump may be driven by any suitable means such as a turbine or electric motor. I have elected to show each driven by an electric motor 15.

It will be noted that a continuous circulation of water from the pipe 7 is maintained through the throwing pump instead of using the same water over and over again, which operation would gradually heat the water. The amount of water which passes through the throwing pump is considerably less than that which passes through the circulating pump so that only a relatively small amount of heat is added to the water due to its passage through the throwing pump and this amount has but a small effect upon the main body of the circulating water flowing through the condenser. The water used for cooling the condenser is discharged back to the source of supply or otherwise, as desired. This means then that the water available for use in the throwing pump has a temperature which is not greater than that employed for circulating purposes; also that the use of an auxiliary vessel or receptacle is avoided, which reduces the necessary space occupied by the apparatus and also avoids the use of a special pump for conveying the discharged water from the throwing pump when the latter is so positioned that its discharge cannot flow freely away.

In Fig. 2, a modified arrangement is shown wherein a relatively small vessel is interposed between the source of cooling water and the throwing pump. Circulating water enters the pump 4 from the pipe 7 as before, a valve 16 being employed to regulate its passage. A certain amount of water from the pipe 7 is discharged into the collecting or equalizing vessel or reservoir 18 by the pipe 19 under the control of the valve 20. The water in the vessel 18 will be cooled to a greater or less extent due to radiation and conduction. The throwing pump 8 instead of receiving its supply of throwing water directly from the supply pipe 7 receives it therefrom through the vessel 18 and a pipe 21, whose lower end is submerged in the vessel and is provided with a strainer 22. The air is conveyed from the condenser by the pipe 11 and is dis-

charged with the throwing water by the conduit 23 into the vessel 18 in which the air is liberated instead of being conveyed with the circulating water through the tubes of the condenser. The amount of water that is contained in the vessel is subjected to the control of a float 24 which is connected by an upright rod with the lever 25 of a valve 26. This valve regulates the passage of water from the vessel through the pipe 27 into the circulating pump 4. The valve 16 or other device so regulates the size of the opening in the pipe 7 that a certain portion of the water in the pump will be taken from the vessel and the remainder from the pipe itself. When the level of the water in the vessel is below that shown, the valve 26 will remain seated but as soon as the level increases above that shown, the valve automatically opens and water is drawn therefrom by the circulating pump 4. The reduction in pressure beyond the valve 16 due to its throttling action also assists in drawing water through the pipe 27. It is to be observed in this case as in the one previously described, that the cooling water conduit system and the pump 8 are connected in parallel as regards the passage of water, hence the advantages set forth in connection with Fig. 1 apply to the arrangement of this figure. This arrangement also has the advantage that the air which is extracted from the vapor space in the condenser is liberated at an intermediate point instead of being conveyed with the circulating water through the pump 4 where it might interfere with its suction.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. In a condensing system, the combination of a surface condenser having tubes and a steam inlet, a conduit and a pump for circulating a fluid through said tubes for condensing the vapor within the condenser, and an air pump of the throwing type for removing air from the vapor space of the condenser, both of said pumps receiving fluid from the same source, and fluid discharged from both pumps passing through the said tubes.

2. In a condensing system, the combination of a surface condenser having tubes and a steam inlet, a pump for circulating a condensing fluid through the tubes, a centrifugal throwing pump for removing air from the vapor space of the condenser, a conduit

that is common to and supplies fluid to both pumps, and a conduit that receives fluid from both pumps and discharges it into the tubes to condense the vapor in said condenser.

3. In a condensing system, the combination of a condenser, a conduit system including a pump for circulating water through the condenser, a centrifugal throwing pump for extracting air from the vapor space of the condenser, the throwing pump receiving its fluid supply from the same source as the circulating pump, and discharging it into the conduit system on the suction side of said circulating pump.

4. In a condensing system, the combination of a surface condenser, a pump for circulating condensing water through the condenser, a centrifugal throwing pump which is piped to the vapor space of the condenser to remove air therefrom, means supplying water to the throwing pump from the source of supply of the circulating pump, and means for conveying fluid discharged from the throwing pump to the suction side of the circulating pump, the throwing pump being connected in parallel with the supply to the circulating pump as regards the passage of water therethrough.

5. In a condenser system, the combination of a surface condenser, a pump for circulating condensing water through it, a centrifugal throwing pump which is piped to the

vapor space of the condenser to remove air therefrom, means for supplying water to the throwing pump from the source of supply of the circulating pump, means for conveying fluid discharged from the throwing pump to the suction side of the circulating pump, the throwing pump being connected in parallel with the supply to the circulating pump as regards the passage of water therethrough, and means for regulating the passage of fluid through the pumps.

6. In a condensing system, the combination of a condenser, a centrifugal pump for circulating water through the condenser, a centrifugal throwing air pump for removing air and vapor from the condenser, a reservoir, conduit means supplying water to the circulating pump and the reservoir, a conduit between the reservoir and the water inlet of the throwing pump, a conduit conveying the discharge from the throwing pump to the reservoir, a conduit for conveying water from the reservoir to the inlet side of the circulating pump, and a float-controlled valve for regulating the flow of water from the reservoir to the last named conduit.

In witness whereof, I have hereunto set my hand this 16th day of June, 1909.

HULDREICH KELLER.
